UNITED STATES PATENT OFFICE

ALBERT C. ROGGE AND HIRAM GORDON, OF COLUMBUS, OHIO

HEEL-SEAT-TRIMMING MACHINE

Application filed September 19, 1928. Serial No. 306,884.

This invention relates to improvements in shoe making machinery, and is particularly directed to an improved automatic machine constructed and adapted for the purpose of trimming the heel seats of shoes preparatory to the application thereto of wooden heels. Wooden heels are provided, almost invariably, with concave upper surfaces, known in the art as heel seats. These surfaces are 5 caved, when viewed in vertical section, in order that the outer edges of the heels may be neatly and closely joined to the heel uppers of shoes. Before the application of the wooden heels, which latter are now widely 10 used in connection with feminine footwear, it is necessary to trim or bevel the lower heel engaging portions of a pair of shoes so that such heel engaging portions will be substantially convex, when viewed in cross-section, 15 to form with the concavity of the heel seats of wooden heel blanks. Heretofore it has been customary on the part of shoe manufacturers for the operator or fitter, by the use of a manually operated knife or cutter, to 20 remove the surplus material from the shoe sole having engagement with the heel seat of a heel. This operation, due to its manually 25 executed character, has been relatively slow and costly and has required the services of skilled shoe operatives in order to permit of 30 proper trimming of the heel and the registration thereof with the outer edges of the heel seat of a heel blank and, therefore, it is a primary object of the present invention to 35 provide an automatic machine for the purpose of effecting quickly and accurately the trimming of the heel seats of shoes in the manner aforesaid for the purpose of expediting the operation, to provide uniform work- 40 manship and to reduce the cost of this operation as compared with the now widely used hand method.

The invention contemplates the provision of a machine of this character provided with 45 a reciprocating cutter together with an improved adjustable support or jack, arranged beneath the cutter, and adapted for the reception of a last containing shoe, the support or jack being so disposed as to permit the shoe to be presented to the reciprocating

cutter to effect the heel seat trimming or beveling operation above set forth in a quick, effective and economical manner, the machine being provided with a guide arranged adjacent to the cutter by which the shoe is 55 guarded while in engagement with the cutter.

Another object resides in the provision of power promotion means formed in connection with the machine for the purpose of reciprocating the cutter, and the provision of improved means for holding the shoe in operative relationship with the cutter, and in various other features which will be in part obvious and in part pointed out hereinafter. 60

For a further understanding of the invention, reference is to be had to the following description and the accompanying drawings, wherein:

Figure 1 is a view in front elevation of the improved heel seat trimming machine comprising the present invention, 70

Figure 2 is a side elevation thereof,

Figure 3 is a vertical sectional view taken through the upper part of the machine, disclosing more particularly the cutter, the shoe supporting jack, and the drive mechanism for the cutter, 75

Figure 4 is a horizontal sectional view taken through the cutter, its guiding and driving mechanism, 80

Figure 5 is a transverse sectional view on the line 5—5 of Figure 3,

Figure 6 is a similar view on the line 6—6 of Figure 3,

Figure 7 is a vertical sectional view taken through the driving connection, 85

Figure 8 is an enlarged vertical sectional view taken through a shoe showing its relation to the movable knife,

Figure 9 is a fragmentary elevational view of a shoe having a preferred heel seat, and 90

Figure 10 is a perspective view of a shoe and a heel showing the shape of the sole after it has been trimmed.

Referring more particularly to the drawings, the numeral 1 designates the base or standard of the heel seat trimming machine constituting the present invention. This standard may be formed from any suitable materials and it is preferably of such height 100

that the operator has control of the operations while occupying a standing position. The lower portion of the standard provides an enlarged base 2 adapted to rest upon any desired foundation. Arranged upon the base 2 to the rear of the standard 1 is an electric motor 3 which is employed to impart power to the various movable units of the machine, although any other suitable form of power imparting mechanism may be utilized. The motor is formed to include an armature shaft 4 to which is fixed a bushing 5 provided with a clutch collar 6. Loosely mounted upon the bushing is a pulley 7 which is also formed 15 with a complementary clutch collar 8, the latter being spaced from the collar 6 by a leather or other suitable type of clutch disk 9. The disk 9 is confined between the collars 6 and 8 and is loosely positioned on the bushing 5. 20 This arrangement is such that when the pulley 7 is forced longitudinally of the bushing so that the disk 9 is placed under compression a frictional clutch relationship is established permitting of the rotation of the 25 pulley 7 substantially in unison with the motor shaft 4.

To control the operation of the pulley 7 there is provided a foot pedal 10 which is pivotally mounted as at 11 on the base 2. One 30 end of the pedal is connected with a bell crank lever 12 which is pivotally mounted as at 13 on the base 2, and the upper end of such lever carries a screw 14 which engages with the outer end of the pulley 7. 35 It will be seen that by pressing downwardly upon the pedal 10 the lever 12 will be rocked so as to force the collars 6 and 8 into clamping engagement with the disk 9 to rotate the pulley 7. When the foot pedal is released a spring 15 is employed to automatically effect disengagement between the collars 6 and 8 and the disk 8, thereby stopping the rotation of the pulley.

Passing around the pulley 7 is a drive belt 45 16 which is also trained over a second pulley 17 mounted upon one end of a crank shaft 18. This shaft is journaled for rotation in connection with bearings 19 mounted upon a bracket 20 projecting from the upper end of 50 the standard 1. The standard 1, contiguous to its upper end, is provided with a bearing 21 in which is slidably mounted a rod 22, one end of which rod, i. e., its inner end, is pivotally connected with a connecting rod 55 23 carried by the crank portion 24 of the shaft 18, the arrangement being such that the rotation of the crank shaft effects positively the reciprocation of the rod 22.

The outer end of the rod 22 is split longitudinally as at 25 for the accommodation of the inner end of a flat longitudinally extending cutting blade 26. Surrounding the split end of the rod 22 is a split sleeve 27 and, as shown in Figure 5, this sleeve is 60 tightened into clamping engagement with the

outer end of the rod 22 and the blade 26 by means of a vertical screw 28. This screw passes through registering opening formed in the sleeve 27, the rod 22 and the blade 26, the lower end of such screw being threaded and received within a threaded opening provided in the bottom of the sleeve 27. By tightening the screw 28 frictional pressure will be exerted on the blade and positively hold the latter in connection with the reciprocating rod 22. The sleeve 27 also grips the sides of the blade to prevent lateral twisting and turning movement on the part of said blade, whereby the latter is maintained in rigid longitudinal relationship with the rod 75 80 22.

The upper end of the standard 1 terminates in a yoke or goose neck 29 which carries, as shown in Figure 6, a horizontally extending guide plate 30, the under surface of which being provided with a groove 31 adapted to receive and guide the intermediate portion of the blade 26 which projects forwardly from the rod 22, confining such blade to longitudinal reciprocatory movement in a substantially horizontal plane. Similarly, the extreme outer portion of the cutter or blade 26 is guided by means of a guide member 32 provided with a horizontally extending opening 33 formed to accommodate the outer end of the blade 26. The guide member 32 is carried in connection with the substantially L shaped bracket 34 adjustably mounted in connection with the forward portion of the yoke 29. It will thus be seen that the spaced guides 30 and 32 co-operate with the cutter or blade 26, which is of thin metallic form, to hold the latter confined except for its required longitudinal reciprocatory movement. By thus limiting the plane of operation of the cutter the machine may be very readily adapted to the operation of trimming heel seats.

In order to support the shoe in connection with the machine and to permit of the proper presentation of the heel seat to the cutter, there is provided a supporting jack 35. This jack includes a vertical screw 36 which is slidably mounted in a plain bore formed vertically in a stationary hub or bearing 37 projecting from the lower part of the standard 1. The screw 36 carries nuts 38, disposed on opposite sides of the bearing 37, nuts being employed for the purpose of controlling vertical operating position of the screw 36. The upper end of the screw 36 is provided with a head 39 upon which is pivotally mounted for compound rocking movement a vertically extending post 40. The upper end of this post is pivotally connected as at 41 to a clevis 42 which, in turn, is pivotally connected as at 43 to a jack stud 44. It will be observed that the pivots 41 and 43 have their axes disposed in perpendicular relationship, which admits of flexibility in the positioning 100 105 110 115 120 125 130

of the stud 44 in addition to the flexibility provided in the connection between the lower end of the post 40 and the screw 36.

In operation, a shoe 45 fitted with an internal last 46 is placed on the stud 44 with the stud positioned in a substantially vertical opening 47 formed in the last. The shoe is then manually moved by the operator of the machine so that the edge portions of its heel structure will engage with a disk shaped guide 48 mounted for rotation upon a vertical axis 49, the latter being carried in connection with a bracket plate 50 which has its inner end adjustably connected with a supporting bracket 51. This bracket, in turn, is mounted for vertical adjustment as at 52, in connection with the standard 1 or its removable head or yoke 29. It will be understood that the adjustment between the bracket members 50 and 51 and the yoke 29 permits the disk 48 to be adjusted advantageously in relation to the cutting blade 26.

The operator applies the lasted shoe to the stud 44 and places the heel portion of the shoe against the disk guide 48. By then rotating the shoe about the axis of the stud 44, while the heel is maintained in engagement with the guide 48, a beveled cut or surface 53 will be produced on the heel engaging portion of the shoe sole, which cut or surface will correspond substantially to the concave heel seat of a wooden heel 54. This operation may be carried out quickly, accurately and economically together with uniform workmanship with the result that the operation of trimming heels will not prove so costly as compared with former or prior methods and at the same time increased production per operative employed in this operation is secured. The blades or cutters 26 when worn, broken or dulled may be readily removed and a new or renewed blade inserted. Furthermore, adjustments provided both in the supporting jack and for the guide member 48 permit shoes of varying styles and size to be readily adapted to the machine.

What is claimed is:

1. A heel seat trimming machine comprising a frame formed to include a pair of spaced horizontally disposed guides, a cutting blade slidably mounted in said guides, power driven means connected with said blade for effecting the reciprocation thereof, a sole engaging guide arranged beneath said blade, and an adjustable shoe supporting jack carried in connection with said frame and disposed beneath the cutting blade.

2. In a heel seat trimming machine, a supporting frame provided with a pair of spaced bearings, a power driven reciprocating cutter slidably mounted in connection with said bearings, said blade projecting through a work-receiving space provided in said frame between said bearings, a sole guide adjust-

ably carried in connection with said frame and arranged beneath said cutter adjacent to said work-receiving space, and a shoe supporting jack mounted for universal movement in connection with said frame below said cutter and in registration with said space.

3. In a heel seat trimming machine, a supporting frame, a yoke shaped cutter head formed with said frame, said cutter head being provided with a pair of longitudinally spaced horizontally extending bearings, a cutter slidably mounted in connection with said bearings, means for effecting the reciprocation of said cutter, a shoe support adjustably mounted below said cutter, and a sole edge guide disk carried by said frame and arranged immediately below said cutter adjacent to one of said bearings.

4. In a heel seat trimming machine, a supporting frame, a cutter head formed with said frame, a crank shaft rotatably mounted in connection with said frame, a cutter holder slidably mounted in bearings formed in said head and reciprocated by said crank shaft, said cutter head being provided with a pair of spaced horizontally arranged bearings, a cutter slidably mounted in said bearings and having the inner end thereof connected rigidly with said holder, a guide disk arranged beneath said cutter, and a universally adjustable shoe supporting jack arranged beneath said cutter.

5. In a heel seat trimming machine, a standard, a yoke shaped cutting head mounted on said standard, said cutter head being provided with a horizontal bearing, a cutter holder slidably mounted in connection with said bearing for movement in a horizontal plane, a crank shaft journaled for rotation with bearings carried by said standard, means for rotating said crank shaft, a connecting rod between said holder and said crank shaft for reciprocating said holder upon the rotation of said crank shaft, the forward end of said holder being provided with a slot, a frictional clamping sleeve surrounding the slotted end of said holder, a flat cutting blade having the inner end thereof received within the slot provided within said holder and positively retained within said slot by said clamping sleeve, a second bearing formed in connection with said cutter head for the slidable reception of said blade, and an outer bearing adjustably carried by said cutter head for slidably supporting the extreme outer end of said cutter blade.

6. In a heel seat trimming machine, a supporting frame, a cutting blade mounted for reciprocation in said frame and confined to a horizontal plane of movement, a guide disk arranged immediately below said cutting blade, and a pair of relatively adjustable sup-

ports for said guide disk for varying the positions of the latter with respect to the cutting blade.

7. In a heel seat trimming machine, a frame, a cutting blade mounted for reciprocation in said frame and confined to a horizontal plane of movement, a pair of spaced bearings for said blade, a rotatable disk shaped sole engaging guide arranged beneath said blade and having its guiding edge protruding outside one of said bearings for engagement with the sole edge of the shoe operated upon, and a horizontally adjustable support for said guide disk for varying the position of the latter with respect to the cutting blade.

8. In a heel seat trimming machine, a supporting frame, a cutting blade mounted for horizontal reciprocation in said frame, a pair of spaced bearings for said blade, the bearings and the frame being formed to provide a work receiving space therebetween through which said blade projects, a guide disk for the sole edge of a shoe adjustably carried in connection with said frame and arranged beneath said cutting blade adjacent to said work receiving space, and an adjustable connection between one of said bearings and said frame by which the bearing may be moved horizontally to vary the width of said work receiving space.

9. A heel seat trimming machine, comprising a standard formed with a horizontal bearing near its upper end, a cutter holder slidably mounted in connection with said bearing for movement in a horizontal plane, means for effecting the reciprocation of said holder, a flat cutting blade carried by said holder and having one end detachably connected therewith, a second bearing carried by said standard for the slidable reception of the extreme outer end of said blade, and a shoe guard arranged immediately below and positioned intermediate the ends of said cutting blade.

In testimony whereof we affix our signatures.

ALBERT C. ROGGE.
HIRAM GORDON.
